UNITED STATES PATENT OFFICE.

FREDERICK E. WELSH, OF BUFFALO, NEW YORK.

PORTABLE BULKHEAD.

Application filed July 20, 1925. Serial No. 44,786.

To all whom it may concern:

Be it known that I, FREDERICK E. WELSH, a citizen of the United States, residing at Buffalo, in the county of Erie and State of New York, have invented a new and useful Improvement in Portable Bulkheads, of which the following is a specification.

This invention relates to portable bulkheads for use in freight cars, warehouses and other places for the purpose of maintaining stacks or piles of crates, boxes or packages of merchandise or other articles intact. The bulkheads are of particular advantage in freight cars and other conveyances for preventing the merchandise or articles from shifting about or falling, and being injured in transit or because of the shocks and motion to which cars and other conveyances are subjected in use.

Portable bulkheads for this purpose heretofore provided are objectionable for one reason or another. For instance, some of these devices are in the nature of frames having portions for engaging with fixed attaching devices which are built in or secured to the floors, roofs or sides of the car, thus rendering such devices useless except in cars or structures equipped with the cooperating attaching devices. Other constructions have been provided with levers or parts adapted to actuate prongs or toothed members which are forced into the walls of the car or structure to secure the bulkhead in place. Both of these constructions are relatively costly, and in addition, the latter type of bulkhead is liable to cause considerable damage to the cars, and obviously could not be employed with metallic car structures now in use. Furthermore, the above mentioned types of devices are designed to engage only with a side or end of the stacks or piles of goods or commodities so that they often become displaced, due to loosening of the fastening means, and all of these devices increase the cost of handling and shipping the goods, owing to the labor and time consumed in placing them in and removing them from, operative positions. Other constructions have been proposed comprising a number of detached or separate, loose frames or sections adapted to interlock with one another without fastening devices or attachments. These loose sections, however, are liable to become disengaged from one another in transit, and the separate sections, when not in use become

scattered about and must be gathered up and assembled in proper relation each time they are to be used.

One object of the present invention is to provide a bulkhead for the purposes described which is adapted for use in protecting and maintaining merchandise or other articles in the desired position in railroad cars, motor tracks and in other places, and which is truly portable and self contained and does not require any fastening means to keep it in position, and which nevertheless will not slip or shift about in transit when used in a moving conveyance.

Other objects are to provide a portable bulkhead which can be quickly placed in position, and which is provided with a base adapted to be engaged beneath a pile or stack of merchandise, and with a folding, upright section or part which is secured to said base part and is engageable with an end of the stack or pile; also to provide the bulkhead with bracing means for said upright section so arranged that pressure exerted against said section tends to firmly hold the bulkhead in position, and prevents its shifting about on the floor or surface on which it rests; also to provide a bulkhead of this character having all of its sections or parts connected together and movable relative to each other, the connections between said parts being such that the bulkhead may be collapsed and folded flatwise so as to occupy the minimum of space when not in use, and whereby the bulkhead can be quickly opened to operative position for use; and also to construct a portable bulkhead having adjustable means adapted to be releasably connected and adjusted for the purpose of holding the movable parts of the bulkhead in operative position, said means being releasable to permit the bulkhead to be folded.

The bulkhead constructions heretofore provided have been formed to extend substantially across the cars or structures from one wall to another. It is often necessary or desirable, however, to arrange the articles or goods in the cars so as to leave an aisle or passage extending from the middle to an end of a car so as to permit the handling of small lot shipments for different destinations during transit.

Other objects of the invention, therefore, are to provide a portable bulkhead which is

proportioned and adapted to meet the above mentioned requirements, whereby the bulkheads may be used singly or in pairs, as for example with one pair for each end of a car 5 with the upright section of each bulkhead disposed transversely of the car adjacent one side wall with a space between them so that the goods or articles may be arranged back of the bulkheads in separate stacks with an 10 aisle or passage between the bulkheads and the goods; also to construct the bulkheads so that when arranged as above outlined, the space between said upright sections thereof may be bridged or closed to provide a structure 15 extending all the way across the car to maintain in position a single stack or pile of goods substantially filling an end of a car; and to provide simple and inexpensive means for bridging the gap between such a 20 pair of bulkheads and which may be readily attached to or detached from the bulkheads; and also to improve and simplify the construction of portable bulkheads in the other respects hereinafter specified and claimed.

25 In the drawings:

Fig. 1 is a fragmentary, transverse, sectional elevation of a railroad car showing therein two of the portable bulkheads embodying my invention, said bulkheads being 30 spaced apart so as to leave an aisle or space between them.

Fig. 2 is a view at right angles to Fig. 1 showing one of the bulkheads in operative relation to a stack of merchandise.

35 Fig. 3 is a view similar to Fig. 1, showing parts extending between and cooperating with a pair of spaced, transversely aligned bulkheads to bridge or close the space between the bulkheads, in accordance with this 40 invention.

Fig. 4 is a side elevation of one of the bulkheads in open or operative position.

Fig. 5 is a similar view thereof, collapsed or folded.

45 Fig. 6 is a plan view of the bulkhead in open or operative position.

The bulkhead of the present invention comprises a flat base section or member 10, a folding section or frame 11 hinged at one 50 end to the base section 10 so as to swing toward and from the same, and a bracing section or member 12 hinged to the folding section 11 so as to be capable of swinging into angular relation therewith. By hinging the 55 section 11 to the section 10, and the section 12 to the section 11, as shown, these sections may be folded or collapsed flatwise one on another as shown in Fig. 5, or may be opened up, with the folding section 11 extending 60 upwardly from the section 10, and the bracing member 12 extending downwardly away therefrom with its free end engaging a part on the base section 10 to brace and support the section 11.

65 The sections 10, 11 and 12 are preferably

constructed of slats or pieces of wood so as to form open frames. For instance, as shown in the drawings, the section 10 comprises two opposite, parallel, longitudinal side bars 15 extending from end to end thereof, and end and intermediate cross slats 16 and 17 which are rigidly connected to the side bars 15 in any suitable manner, as for example by bolts 18. If desired, an intermediate longitudinal bar 19 may be provided. The folding section 11 comprises opposite, parallel, longitudinal side bars formed of pairs of spaced, superposed slats 20, and spaced cross bars or slats 21 preferably disposed between and rigidly secured to the bars 20 and extending from one of the side members to the other. An intermediate longitudinal bar 22 is also preferably provided which extends midway between the side bars from end to end of the section 11 and is secured to the cross bars 21. The bracing member 12 shown comprises a pair of parallel side bars 26, and a cross bar 27 rigidly secured to the bars 26, preferably between their ends. The upper ends of the side bars 26 of the brace are connected, as by hinges 28 to the side bars of the folding section 11, so that when the sections are in open position, shown in Fig. 4, the brace is capable of extending downwardly away from the section with the lower, free ends of the bars 26 bearing on the upper face of the section 10. The base section 10 is provided with a transverse bar or abutment 31, which forms a stop against which the free ends of the brace may abut, so that the brace may be held firmly in place, and be prevented from slipping outwardly due to pressure exerted on the brace through the upright section 11. Any other suitable form of stop may, however, be provided to prevent outward movements of the brace 12. Adjustable securing means are preferably provided for securing the sections of the bulkhead in 90 their open or operative relation so as to prevent the bulkhead from collapsing when it is moved from one position to another or when the piled articles are removed from against the upright member. Preferably a chain 32, or other flexible member is used and is fastened at one end at 33 to the section 11, and is provided at its free end with a hook 34. By passing the free end of the chain through a ring 35, secured to the stop bar 31 the chain may be drawn taut and the hook 34 secured in a link of the chain, thus preventing the sections 11 and 12 from 95 swinging on their pivots and collapsing.

The base 10 of the bulkhead is adapted 100 to extend beneath and be held down by a part of a stack or pile of goods, while the folding section 11 thereof engages against an end or side of the stack. This is accomplished, in the construction shown by hinging the section 11 to the section 10 between 105 110 115 120 125 130 135

the ends thereof as by the hinges 38, so that when the section 11 is moved to an upright position, see Fig. 4, the base section 10 extends horizontally to opposite sides of the upright section 11.

Figs. 1 and 2 illustrate the manner in which the bulkhead is employed. A represents cases or boxes of goods arranged in a stack extending from the end wall toward the center of the car B, the side of the stack being preferably disposed against a side wall C of said car. After a portion of the goods have been stacked or arranged in the car, the base 10 of the bulkhead is placed on the floor D with one end extending toward the end wall of the car, and the upright section 11 extending substantially perpendicular to the side wall, as shown, with its unobstructed face towards the boxes A. A part of the shipment of goods is now piled upon that portion of the base section of the bulkhead which extends toward the adjacent end of the car, and the formation of the stack continued until the space between the end of the car and the rear face of the upright section 11 is substantially filled, so that the boxes or goods not only bear against the section 11, but rest on a part of the base as well. Consequently, pressures exerted against the section 11 by the goods and tending to shift or tip the bulkhead are resisted by the weight of the goods resting on the base section, as well as by the bracing section 12. Moreover, by means of the construction described, the outward pressures exerted on the upright section of the bulkhead are transformed into downward pressures through the brace 12 and the stop member 31 and tend to press the outer end of the bulkhead more firmly on the supporting surfaces and the pressure on the section 11 is further resisted by the weight of the goods resting on the base section. The bolts 18 extending below the bottom face of the section 10, have a tendency to firmly grip the surface on which the bulkhead rests and acts to prevent the bulkhead from slipping.

One of the important advantages of the bulkhead described and shown in the drawings is its adaptation for use in express and mail cars where packages or goods must be taken on and off in transit. In such cases, an aisle or space must be provided to permit the passage of the attendants from the center to the ends of the car. Where such requirements are necessary two of the bulkheads may be arranged (as shown in Fig. 1) at opposite sides of the car in spaced relation so that the goods may be piled in two separate stacks back of the bulkheads, thus leaving an aisle or passage from the center to the end of the car.

If, however, it is necessary or desirable for the entire end or ends of the car to be

piled or filled with goods, this may be done by arranging a pair of the bulkheads side by side in spaced relation with their upright sections in the same vertical plane and providing means, in accordance with this invention, for bridging or closing the space between said upright sections 11. The means shown for this purpose comprise a plurality of detachable slats or horizontal rails 45, see Fig. 3, which are slipped endwise into place between the spaced slats 20 of the side bars of the sections 11 and rest on the horizontal cross rails 21 thereof. Registering holes are preferably formed in the upright slats 20 and in the detachable bars 45 for the reception of suitable detachable securing devices or pins 46 adapted to prevent endwise movement and unintentional displacement of the cross rails 45. Any other suitable, quick, detachable securing devices may, however, be provided for the detachable bars bridging the gap between the spaced bulkheads.

The chain 32, in addition to its use for the purpose described, may also be employed for maintaining the bulkhead collapsed or folded, so that it will not accidentally open up, by passing the chain around the adjacent transverse slats of the sections 10, and 11 and the brace 12 and securing the hook in one of the links, as shown in Fig. 5.

I claim as my invention:

1. In a portable bulkhead of the character described, the combination of a base section, a folding section disposed transversely thereof and adapted to extend upwardly therefrom, said folding section being movably connected at its lower end to said base section, and a bracing member which is movably connected at one end to one of said sections and is adapted to extend at an angle therefrom with its free end releasably engaging said other section to brace said upright section.

2. In a portable bulkhead of the character described, the combination of a base section, a folding section disposed transversely thereof and adapted to extend upwardly therefrom, said folding section being movably connected at its lower end to said base section, and a bracing member which is movably connected at one end to one of said sections and is adapted to extend at an angle therefrom, and an abutment on said other section against which the free end of said bracing member is adapted to bear to prevent movement of said bracing member when pressure is exerted against said upright section.

3. In a portable bulkhead of the character described, the combination of a base section, a folding section disposed transversely thereof and adapted to extend upwardly therefrom, said folding section being movably connected at its lower end to said base sec-

tion, a bracing member which is movably connected at one end to one of said sections and is adapted to extend at an angle therefrom with its free end releasably engaging 5 said other section to brace said upright section, and releasable means for preventing the unintentional disengagement of said bracing member from said other section.

4. In a portable bulkhead of the character 10 described, the combination of a base section, a folding section disposed transversely thereof and adapted to extend upwardly therefrom, said folding section being movably connected at its lower end to said base 15 section, a bracing member which is movably connected at one end to one of said sections and is adapted to extend at an angle therefrom with its free end releasably engaging 20 said other section to brace said upright section, and a flexible member secured to one of 25 said sections and adapted to be adjustably connected to said other section so as to be drawn taut to hold said bracing member firmly in bracing position.

5. In a portable bulkhead of the character 30 described, the combination of a base section, a folding section disposed transversely thereof and adapted to extend upwardly therefrom, a connection between said folding section and said base section for permitting 35 relative swinging movements therebetween, a bracing member, a connection between said bracing member and one of said sections for permitting 40 said bracing member to swing relatively to said section to and from a position in which it extends at an angle from said section towards and releasably engages said other section to brace the folding section, and a flexible member secured to 45 one of said sections and adapted to be fastened to said other section to hold said bracing member and said folding section in position, and said connections between said base section and said upright section, and between 50 said bracing member and one of said sections being constructed to permit said sections and said member to be folded flat-

wise one upon another, when said flexible member is disconnected.

6. In a portable bulkhead of the character 55 described, the combination of a base section, a transverse article engaging section adapted to extend upwardly therefrom, a bracing section extending angularly from said article engaging section, said base section having an inner portion projecting beyond one side of said article engaging section and adapted to extend beneath and engage the articles, and an outer portion projecting beyond the opposite side of said article engaging section and on which said bracing section is adapted to bear, whereby outward pressures exerted by the articles against said article engaging section are converted into downward pressures through said bracing 65 section to force the outer portion of said base section firmly against the surface on which the bulkhead rests.

7. In a portable bulkhead adapted to maintain a stack of articles in position, the 70 combination of an upright section engageable with an upright face of the stack, a base section to which said upright section is connected and which is adapted to rest on a supporting surface, and having a portion 75 extending beneath and engaging articles in said stack, and a bracing section engaging with and extending between said other sections.

8. In a portable bulkhead adapted to 80 maintain a stack of articles in position, the combination of an upright section engageable with an upright face of the stack, a base section to which said upright section is connected and which is adapted to rest on a 85 supporting surface, and having a portion extending beneath and engaging articles in said stack, a bracing section engaging with and extending between said other sections, and a flexible and adjustable member for 90 releasably securing and maintaining said sections in operative relation.

FREDERICK E. WELSH.
